HIDE AND SKIN WORKING MACHINE
EMPLOYING ROTATING ROLLS

Robert F. Whitney, Winchester, Mass., assignor
to The Turner Tanning Machinery Company,
Portland, Maine, a corporation of Maine

Application August 22, 1951, Serial No. 243,101

14 Claims. (Cl. 69—42)

1

This invention relates to machines for treating hides and skins, and more particularly to machines employing rotating rolls for performing such operations as fleshing, unhairing, scudding or setting. It will be understood, however, that important features of the invention may have other applications and uses in the tannery field.

In general, tannery machinery must operate under conditions which are difficult in so far as maintenance and repair of the machines are concerned. It has also been found in the past that machines for treating large pieces of work were not as acceptable in treating small pieces for the reason that each small work piece or a side of leather, when treated in such machines, would often be thrust to one side of the desired line of feed and damaged. In many tannery machines another difficulty is encountered in that the operators must employ considerable manual force in initiating a change in each machine operation cycle with consequent physical fatigue resulting, the cycle change in the machine moreover, frequently causing the machine parts to clash or to act abruptly on the work piece. The result is an undesired effect on the quality of the work produced and considerable strain and wear of the mechanical elements involved.

It is an object of the present invention to provide an improved tannery machine having an arrangement of parts which are readily accessible for repair and maintenance as well as being adjustable to compensate for the wear of rolls which form main parts of the machine. As herein illustrated the machine is provided with a novel roll and roll arrangement for optionally feeding and treating either large or small work pieces. It is a further object of the invention to provide a machine with an improved fluid-pressure control mechanism for opening and closing the work treating rolls smoothly and without fatigue on the part of the operator.

To the above ends and in accordance with important features of the invention, a novel system or arrangement of work treating rolls and supporting members is provided which is driven by power means located high on the machine free of dirt and debris and readily accessible for adjustment, replacement or repair. Another feature is a novel feed-roll having longitudinal and helical grooves which serves in combination with a rubber surfaced bed roll to feed and hold the work along the desired path of feed. A further feature comprises an improved arrangement for conveniently shifting a pinch roll in and out of operative relation to the other rolls with no

2

interference in respect to the introduction of work to be treated, thereby providing, at will, either a long or short grip for treating large or small work pieces respectively. As an added feature there is provided a feed roll adjustably mounted to compensate for wear without influencing work pressure on the bed roll thereby maintaining quality of the work done. Another feature of the invention is an improved fluid pressure system utilizing a valve with a plunger having annular grooves to provide smooth control of a tannery machine employing work treating rolls.

The invention will now be more particularly described by reference to the accompanying drawings and thereafter pointed out in the claims.

In the drawings,

Fig. 1 is a view in front elevation of a machine embodying the present invention, with parts broken away for ease of illustration and with the work-engaging rolls shown in their closed, long-grip positions;

Fig. 2 is a sectional view on an enlarged scale along the line II—II of Fig. 1 at the right-hand end of the machine and also with parts broken away;

Fig. 3 is a sectional view (drawn to the same scale as Fig. 1) along the line III—III of Fig. 1 at the left-hand end of the machine;

Fig. 4 is a view of some of the parts as shown in Fig. 3 but with the rolls in open positions and with a work piece placed in position for subsequent treatment;

Fig. 5 is a section along the line V—V of Fig. 1 but showing only some of the parts with the rolls in open positions and ready for short-grip operation with a work piece positioned for treatment upon subsequent closure of the rolls;

Fig. 6 is a section similar to that shown in Fig. 5 but with the rolls in closed positions and a work piece being treated;

Fig. 7 is a more complete view in elevation of some of the fluid-pressure apparatus shown partially and during a different portion of the machine cycle in Fig. 2;

Fig. 8 is an enlarged sectional view along the line VIII—VIII of Fig. 2;

Fig. 9 is a section through the control valve, drawn to a larger scale, along the line IX—IX of Fig. 1;

Fig. 10 is an enlarged view of a portion of the feed roll shown in Fig. 1;

Fig. 11 is a section along the line XI—XI of Fig. 10; and

Fig. 12 is an enlarged section along the line XII—XII of Fig. 1.

The machine as illustrated includes a frame comprising two main castings 10 and 12 and end members 14 and 16 (Fig. 1) the latter being made up of channel bars. Supported on the main castings 10 and 12 are two horizontal and transversely extending channel bars 18 and 20 (Fig. 2) which tie the end members of the frame together and on their ends support the vertical end frames 14 and 16. The tops of the main castings 10 and 12 are rigidly joined together by means of channel bars 22 and 24 (Figs. 2 and 3) and a tie shaft or hand rail to be described.

At the left-hand end of the machine and adjustably mounted with relation to the channel bars 22 and 24 by means of studs 30 is a horizontal plate 26 for supporting an electric motor 28. An L-shaped bracket 32 is provided for supporting a bearing block or pillow block 34 with a horizontal leg 33 of the bracket 32 being attached to the bars 22 and 24 beneath the plate 26. In alignment with the bearing 34 is a second bearing 38 (Fig. 1) supported by a bracket 40 having a horizontal leg 41 (Fig. 2) attached to the top of the channel bars 22 and 24. The end frame members 14 and 16 support bearings 42 and 44 (Fig. 1) to cooperate with the bearings 34 and 38 in supporting a shaft 46 running the full width of the machine. The shaft of the motor 28 is provided with a small diameter set of pulleys 48 (Fig. 3) as well as with a larger diameter set of pulleys 50. The set of pulleys 48 is connected by belts 52 to a larger set of pulleys 54 mounted on the shaft 46 to drive the same. Between the bearings 38 and 44 and keyed to the shaft 46 is a set of pulleys 56 which is connected by belts 58 to large pulleys 60 (Fig. 2) for driving a clutch unit on a counter shaft 62. The latter shaft is mounted in bearings on the main casting 12 and end casting 16. One of these bearings (64) is shown in Fig. 1. The shaft 62 is also provided with a set of pulleys 66 rotatable therewith for driving a set of pulleys 67 by means of belts 68. The pulleys 67 are keyed to a long sleeve 70 mounted on a fixed shaft 71 which is clamped in position at 72, 74 and 76 (Fig. 1) on the frame members 10, 12 and 16, respectively. The shaft 71 constitutes the tie shaft or safety hand rail previously mentioned.

Two swinging arms 78 and 80 are mounted freely to rotate at their upper ends on the fixed shaft 71. Swinging arm 78 is adjacent to and parallel with the main casting 10 and the swinging arm 80 is adjacent to and parallel with the main casting 12. The swinging arms are identical in construction and therefore only one of the arms is specifically described herein. The arm 78 is U-shaped in cross section (as considered in a horizontal plane through its intermediate portion) and within the sides of the arm 78 is mounted a short shaft 82 upon which is mounted for relative rotation an arm 84 the end of which serves as one bearing for the shaft 88 of a pinch roll 90. The end of the arm 84 is also provided with a rounded protuberance 92 upon which a spring-loaded plunger 94 is adapted to rest. The plunger 94 includes a shaft 96 mounted and slidable with respect to the swinging arm 78 in such a way as to tend to rotate the arm 84 by virtue of spring compression release in a counterclockwise direction as viewed in Fig. 3. The degree or extent of spring compression is adjustable and the range of movement of the plunger 94 is such that the pinch roll 90 may press against the work

being treated and, in the absence of such work, the plunger 94 is held just clear of the protuberance 92 beneath it when the rolls are in closed position.

5 The upper end of the arm 78 is provided with a bearing bracket 100 for supporting in rotatable relation therewith one end of a shaft 102 which serves to connect the two swinging arms 78 and 80. As inferred above, the swinging arm 80 has 10 a bearing bracket 101 (similar to bracket 100) to cooperate in rotatively supporting the shaft 102 and is provided with a spring-loaded plunger 97 as well as with a short or pivot shaft 83 and a pinch roll supporting arm 85 pivoted on the shaft 83.

On the lower portion of the swinging arm 78 (Figs. 3 and 4) is mounted a bearing block or pillow block 104 and this block, in cooperation with a block 105 (Figs. 5 and 6), on the arm 80, 20 supports a rubber-covered bed roll 106 on its shaft 108.

Each end of the shaft 102 is provided with a lever 110 or 112 to rotate therewith. The end of the lever 110 is pivoted at 114 to a chain 116 (Figs. 3 and 4) and the other end of the chain is attached by means of a bolt 118 to the end of the arm 84. The other end of the shaft 102 is similarly connected to the arm 85 by means of a chain 120. Near the longitudinal center of the shaft 102 and in nonrotatable relation therewith is mounted a hand lever 122.

Pivoted at 124 (Fig. 3) at the lower end of the swinging arm 78 is a trunnion or bearing block 126 for supporting in slidable relation a connecting rod 128. A headed sleeve 130 is threaded on the connecting rod 128 and is arranged to slide in the trunnion or bearing block 126 and coaxially bears a coil spring 132 under compression between the bearing block and a nut 134 adjustably threaded on the sleeve 130. Lock nuts 135 are provided to hold the sleeve 130 in adjusted position on the rod 128. The rod 128 is pivoted at 136 to a crank arm 138 attached to a shaft 140, the latter being mounted in bearings 142 and 144 (Fig. 1) as well as in a separate bearing 145 (Fig. 2). The bearings 142 and 144 are attached to brackets 146 and 148 affixed to the main castings 10 and 12, respectively, and the bearing 145 is supported on frame members to be described.

50 It will be understood that the lower end of the swinging arm 80 is pivotally connected at 149 (Fig. 2) to a connecting rod 150 arranged to cooperate with the connecting rod 128. One end of the rod 150 is pivoted to a crank member attached to shaft 140. This crank member and associated instrumentalities will be described hereinafter and are shown in Fig. 7.

The extreme lower end of the swinging arm 78 is provided with an adjustable stop screw 152 (Fig. 3) for contacting an abutment 154 on the main casting 10. The swinging arm 80 has a stop screw 156 (Figs. 1 and 2) which is adapted to function as does screw 152 but in relation to an abutment 157 on the casting 12.

65 The main or left-hand casting 10 has bolted thereto two brackets 158 and 160 (Fig. 3) upon which are mounted two resilient rubber bumper pads 162 and 164, respectively. These pads are held on their corresponding brackets by means of adjustable stop screws 166 and 168. The bolts are adjusted so that they do not extend to the top surfaces of the rubber blocks and the latter are in the plane of rotation of the crank arm 138 to serve as auxiliary stops therefor. Rubber bumper blocks are not provided at the other

end of the shaft 140 and, in fact, have not proved to be essential at either end. They are of assistance, however, in setting up the machine and making adjustment.

The pulleys 59 (Fig. 3), mounted on and driven by the shaft of the motor 28, are connected by means of belts 170 and pulleys 172 to a shaft 174 of a conventional helical bladed work treating roll 176. The shaft 174 carries a fly wheel 178 and is mounted in pillow blocks or bearing blocks 180 (Fig. 3) and 182 (Fig. 2) which are bolted in place on the main castings 10 and 12, respectively, as well as in a bearing 184 (Fig. 1) mounted on a channel bar 185 attached to the frame member 14.

Pivottally mounted on the main castings 10 and 12 are curved arms 186 and 188, respectively. The pivotal mounting for the arm 186 (Fig. 3) consists of an eccentrically mounted bearing 190 which permits adjustment for wear. A similar eccentric adjustment bearing 192 is provided for the curved arm 188 (Fig. 2). The curved arm 186 at its intermediate portion is provided with a bearing 200 for one end of the shaft 202 of a special feed roll 204. The other end of the shaft 202 is journaled in a similar manner in the curved arm 188, but, in addition, bears a sprocket 208 (Fig. 2) which in turn is connected to a shaft 210 (Journaled in bearings 212 and 214 on the frame members 12 and 16) by means of a chain 216 and a sprocket 218. Two meshing gears 220 and 222 serve to connect the shaft 210 and the sleeve 70. The gear 222 is fixed to the sleeve 70 which also carries a sprocket 224. The gear 220 and the sprocket 218 are mounted to rotate together on and with the shaft 210. An idler sprocket 226 (Fig. 2) is resiliently mounted in engagement with the chain 216 to maintain the proper tautness therein.

Depending from the top of the main casting 10 and swivelly mounted therein is a rod 230 (Fig. 3) which is adapted to be held downwardly by a coil spring 232 surrounding the rod and mounted under compression between a washer 234 bearing against the under side of a cap member 235 on the casting 10 and a nut and washer assemblage 236 on an intermediate portion of the rod 230. The lower end of the rod 230 is provided with a yoke 240 which is pivoted at 242 to an intermediate portion of the curved arm 186. The curved arm 188 is also adapted to be held in a lowered position because of action of a coil spring (not shown), a rod 245 upon which is coaxially mounted the coil spring just referred to and a pivoted yoke 246.

The end of the curved arm 186 (Figs. 3 and 4) remote from the bearing 190 is in the form of an inclined finger 250 which is arranged to come into engagement with a roller 252 on the shaft 88. An inclined finger 290 (Figs. 5 and 6) forms a part of the curved arm 188 and, in a manner similar to that of finger 250 with respect to the roller 252, is adapted upon the proper occasion to engage a roller (not shown) at the other end of the shaft 88.

At the right-hand end or side of the machine and between the main casting 12 and the end frame member 16 are mounted two short channel bars 260 and 262 (Fig. 2) which are attached to the channel bars 18 and 20, respectively. The channel bars 260 and 262 in turn support a channel bar 264 (Fig. 1) and two angle bars 266 and 268. The angle bars 266 and 268 not only serve to stiffen the machine frame but also serve as a means of support for a vertical frame comprising

ing a vertical channel bar 270 and an upwardly and forwardly inclined channel bar 272 (Fig. 2). The upper ends of the latter two bars are joined by an angle bar 274 to which is pivoted by means of an eye bolt and nut arrangement 276 the upper end of a fluid pressure motor 278. The fluid pressure motor is of conventional design, and a piston rod 280 thereof is pivotally connected by means of a yoke 282 to a crank arm 284 rigidly mounted on a rocker shaft 288 to which is attached a gear segment 286. The shaft 288 in turn is journaled in pillow blocks or bearing blocks 290 (Fig. 1) and 292 (Fig. 2) supported on the machine frame. The teeth of the gear segment 286 (Fig. 7) are in mesh with the teeth of a second gear segment 296 which in turn is affixed to the crank shaft 140. The gear segment 296 bears a crank arm 304 to which is pivoted a curved element or gooseneck 306 (Fig. 7) the end of which is pinned at 308 to the connecting rod 150. At the pivot between the arm 304 and the member 306 is mounted a pin 310 upon which a roller 312 may rotate. The length of the pin 310 is mounted in radial relation with respect to the shaft 140 and gear segment 296.

Transverse to the back of the channel bar 264 (Fig. 7) are mounted two angle bars 313 and 314 the vertical flanges of which are spaced to form a guideway for the end of a swinging lever 316. The latter is pivoted on a bolt 318 extending from a bracket 330 mounted on the channel bar 24. The lever 316 is made up of two metal strips joined for the major portions of their lengths but separated to receive the shipper or shifter 324 between them and in pivoted relation thereto. The shipper 324 is slidable on the shaft 62 and is part of a clutch-brake unit 326 having a brake portion 326B (Fig. 1) and a clutch portion 326C. The clutch-brake unit 326 does not form a part of the present invention and is therefore not specifically described but an equivalent unit is described in the United States Letters Patent No. 2,271,656, granted in the name of George E. McLaughlin. Another unit which could be used is manufactured by The Carlyle Johnson Machine Co., Manchester, Connecticut, and is called a "Maxitorq" double type clutch. Another is a unit sold by the Magnetic Mfg. Co. of Milwaukee, Wisconsin. The arrangement in the present instance is such that the brake portion 326B comes into action and is effective on the shaft 62 and the pulleys 66 when the lever 316 and the shifter 324, with the bolt 318 as a pivot, are shifted toward the main casting 12. If the lever is shifted toward the end frame 16 then the clutch unit 326C is effective to cause the pulleys 66 to rotate the pulleys 66 through the shaft 62. A spring 330 is connected to the frame casting 12 and to the lever 316 to urge the lever toward the braking position. Attached to the lower end of the lever 316 is an angle bar 332 to one flange of which is affixed by bolts 333 and 334 an arcuate cam plate 336. The plate 336 forms an arc to conform with the arcuate travel of the roller 312 but its upper end is bent toward the frame member 16.

Pivoted at 340 to the hub of the crank arm 284 is a link 342 the upper end of which is pivoted at 344 to a plunger 346 of an exhaust valve 340. The casing 350 of the valve 340 is cylindrical and is supported from the angle bar 272 (Fig. 2) by means of a plate 352. Spaced inlet ports 354 and 356 (Fig. 8) as well as corresponding spaced outlet ports 358 and 360 are provided in the valve 340 casing or cylinder 350. The plunger 346 is a

sliding fit within the cylinder 350 and is made with two annular and relatively wide exhaust grooves 362 and 364, the groove 362 being adapted to form a direct passage between the ports 354 and 358 when the plunger 346 is in a lowered position and as shown in Fig. 8. The groove 364 forms a direct passage between the ports 356 and 360 when the plunger 346 is in a raised position as in Fig. 7. Intermediate the two annular grooves 362 and 364 on the plunger 346 are two sets 366 and 368 of smaller grooves, the set 366 having eight grooves and the set 368 having two grooves in the particular embodiment illustrated. A closure cap 370 is pressed down on the top of the casing 350.

The ports 354 and 356 are connected by means of pipe lines 372 and 375 to the exhaust ports 386 and 388 respectively (Fig. 9) of a control valve 380 mounted on the angle bar 270. The valve 380 is conventional and has end caps 382 and 384 including the exhaust ports 386 and 388 and a main body which has an inlet port 390 as well as two ports 376 and 378. A coiled spring 392 is employed under the cap 382 and is mounted to bear against the end of a valve spindle 394 having two valve lands 396 and 398.

Pivoted by means of a pin 400 to the valve spindle 394 is a depending rod 402 the lower end of which is swively attached at 404 (Fig. 1) to one end of a treadle 406. The treadle is pivoted on a bolt 408 affixed to the channel bar 40.

The port 376 of the control valve 380 is connected to the cylinder top of the motor 278 by means of a hose 410 and the port 378 is connected to the motor cylinder bottom by a hose 412.

An air filter or fluid purifier 414 is mounted above the control valve 380 through which air is led from a fluid pressure supply source. Fig. 2 clearly shows a pipe 416 for air entering the purifier and a pipe line 418 for conducting air from the purifier into the port 390 (Fig. 9) of the control valve 380.

The main castings 10 and 42 are formed with appropriate openings 430 (Fig. 3) and 432 (Fig. 2) respectively, permitting the insertion, removal or operative swinging motions of the swinging arms 78 and 80 and their associated parts. The bearing blocks 180 and 182 for the bladed roll 176 are also located in these openings 430 and 432.

The feed roll 204 is of special construction in that parallel grooves 434 (Fig. 11) are employed longitudinally of the roll in combination with helical grooves 436. Each longitudinal tooth or ridge between adjacent grooves 434 is similar in cross section to that of an involute gear tooth, and the helical grooves 436 are defined by right angled shoulders directed toward the center of the machine as depicted by the dot-and-dash lines A shown in Fig. 12. A suitable diametral pitch or pitch number (number of teeth per inch of diameter of pitch circle) for the longitudinal teeth is sixteen.

The long sleeve 70 (Fig. 2), in addition to the pulleys 67, the sprocket 224 and the gear 222, drives an adjustable pitch sheave or pulley 450 which is connected to a pulley 452 on the bed roll shaft 108 by a belt 454. By changing the effective diameter of the pulley 450, the rubber or bed roll 106 may be driven with the same surface speed as the feed roll 204 despite wear of the rubber surface or a reduced diameter of the roll 106.

In order to provide means for driving the pinch roll 90, the shaft 88 thereof is extended beyond

the arm 80 and is provided with a pair of sprockets 460 driven by a pair of short chains 462 (Fig. 2), a longer chain 466, one intermediate large sprocket 468 and a set of two smaller sprockets 470. The longer chain 466 is adapted to be driven by the sprocket 224 and drives the sprockets 468 and 470 which are rotated as a unit on the pin 83. The pin 83 protrudes from the arm 80 and is of a length to provide adequate bearing area for the sprockets.

The arrows shown in Fig. 6 illustrate the directions of rotation of the work treating roll and feed of a work piece WS being fed between the rubber covered bed roll 106 and the feed roll 204 (to the right as viewed in that figure). It will be noted that the bladed roll 176 operates counter to the direction of work feed and that the feed roll 204 operates in the direction of the work feed. In this connection, and as shown in Fig. 1, the helical spiral blades of the roll 176 are divergent and to the right and left hands such that the tendency of that roll is to spread the work on the bed roll 106. At the same time it will be noted that the helical grooves 436 of the two halves of the feed roll 204 are also to the opposite hand but the direction of rotation of that roll is such that the tendency of the sharp or right angled shoulders (effective on the work in the directions of lines A in Fig. 12) is to counteract any off-balance spreading effect of the bladed roll 176. This matter will be further explained in the following description of the machine operation.

In treating a work piece WL of large area such as a side, and assuming the motor 28 is driving the bladed roll 176 constantly, the piece is deposited and draped by an operator over the pinch roll 90 when the machine rolls are in open positions and the main operative parts are in the positions shown in Fig. 4. At this time the lever 422 is or has been placed in a vertical position (as in Figs. 1, 3 and 4) and the chain 416 is ineffective thereby permitting the pinch roll 90 to be lowered by the force of gravity and ultimately guided by the inclined shoulders on the ends 250 and 290 of the arms 186 and 188, respectively. In order to trip the machine and close the rolls into the positions shown in Fig. 3, the operator depresses the treadle 406 with the result that the valve spindle 394 (Fig. 9) rises and air under pressure is permitted to flow from the filter unit 414 through the control valve 380 by way of the ports 390 and 376. This causes the motor 278 to come into operation and the piston rod 280 is pushed downward by the air pressure into the position shown in Fig. 2. Simultaneous with the introduction of air to the motor cylinder through the hose 410 air is exhausted from the motor cylinder through the hose 412 and ports 378 and 388 of the valve 380 and the pipe 375 and ports 356 and 360 (Fig. 8) directly to the atmosphere. This action of the motor 278 causes the swinging arms 78 and 80 to rotate rearwardly on the machine and close the rolls thereby confining the work piece WL between the bed roll 106 and the bladed roll 176. The end roller 252 and the corresponding roller (at the other end of the pinch roll 90) are caused to roll up on the inclined surfaces of the arms 186 and 188 and the grooved feed roll 204 inserts itself between the bed roll 106 and the pinch roll 90, giving considerable wrap-around of the work (almost 180°) which provides the essential long grip for large work pieces which pieces must be firmly grasped and steadily fed while under treatment. As the

rolls close, the plungers 96 and 97 become effective to cause the pinch roll 90 to hold the work with sufficient firmness. Simultaneous with the roll closure, shipper 324 is shifted toward the right end of the machine by action of the roller 312 on the cam plate 336. The brake unit 326B is thereby released and the clutch unit 326C operates to drive the three rolls 106, 204 and 90. The trailing half of the work piece WL is thereby treated by the bladed roll 176 and the operator, upon completion of treatment of that portion, opens the rolls of the machine. The opening of the rolls is smoothly accomplished merely by releasing the treadle 406 at which time the operation of the motor 278 is reversed because of the action of the spring 392 in the control valve 380. The spring 392 pushes the valve spindle 394 downwardly and the treadle 406 upwardly. The operator then may reinsert the work piece WL, after reversing it end for end, for treatment of the other half thereof by again closing the rolls.

The action of the plunger 346 of the exhaust valve 348 is such as to provide a shock absorbing effect in so far as action of the motor 278 is concerned and during either opening or closing of the rolls. The annular grooves or channels 366 and 368, by their number and size, regulate the amount of air which may be exhausted around the plunger 346 and the desired smoothness, rapidity of action and cushioning effects may easily be secured by appropriately varying the nature and location of the channels to suit particular requirements. The arms 78 and 80 tend to open the rolls part way (roughly one-third of the swing) by the action of gravity alone due to the manner of their mounting and so little or no power is required at the corresponding end of the motor stroke in opening the rolls. In closing the rolls, however, considerable power is needed in securing adequate pressure upon the leather and the exhaust to port 358 should be fully open as in Fig. 8. It will be noted, however, that ports 358 and 360 may be easily throttled to avoid shocks at either end of the motor stroke by appropriately modifying the spacing, number or sizes of the annular channels in the plunger 346.

In order to treat a small piece of work WS the long grip effect of the pinch roll 90 is not required and in order to eliminate it the operator merely pulls down on the lever 122 and the consequent through dead-center action of the linkages on the chains 116 and 120 lifts and holds the pinch roll 90 against the action of the spring pressed plungers 96 and 97. The pinch roll, in such a case, is therefore of non effect in so far as the operation of the machine is concerned. The small work piece WS is placed in position on the soft rubber bed roll 106, as shown in Fig. 5, with the rolls open. Upon treading the machine the motor 278 causes the rolls to close and be placed in the positions shown in Fig. 6. The work is firmly grasped between the bed roll 106 and the feed roll 204 and the work roll 176 treats the trailing half of the work. Release of the treadle 406 then causes the rolls to open and the operator reverses the work piece end for end and reinserts the untreated portion of the work piece and closes the rolls by again treading the machine.

During the treatment of the small piece of work WS, and particularly if such work piece is not accurately placed in the central zone of the path of feed (which path is broad optionally to accommodate either large or small pieces), the piece may be thrown to one side by off-balance action of the helical blades and damaged. The

sharp shoulders formed on the feed roll 204 because of the grooves 436, constitute barbs for holding the work properly in the path of feed. The barbs serve to direct or retain the work along a path of feed normal to the axes of the rolls—i. e., they serve to resist any tendency of the work bodily to slip or move sideways or laterally towards either end of the feed roll.

The stationary mounted work treating roll 176 is connected to the motor 28 in such a way that it is constantly rotated in the direction shown by the arrows in the drawings, that is, counter to the direction of feed. In regard to the pinch roll, feed roll, and bed roll, however, they are rotated (in the directions shown by the arrows in Fig. 6) only when the machine rolls are in "closed" or operative positions and their rotation at that time is brought about by the action of the clutch portion 326C of the clutch brake unit 326. When the treadle 406 is released, the rolls open and the shipper 324 is shifted by the spring 330 and the brake portion 326B comes into operation to stop the rolls 90, 204 and 106 for the convenient and immediate insertion of the work by the operator. The throw of the lever 316 to induce driving action is prompted by action of the roller 312 on the cam plate 336 and as a consequence there is essentially no neutral position for the clutch brake unit 326, i. e., the rolls 90, 204 and 106 are either being rotatively driven or are restrained by the brake.

It will be appreciated that if a high quality of work is to be maintained together with smoothness in machine operation the axes of the tie-shaft 71, the feed roll 436, and the bed roll 106 should all lie in the same plane while the rolls are in closed or working positions. This plane is represented by the dot-and-dash line AB of Fig. 3. The eccentric mounting of the curved arms 186 and 188 at 190 and 192 respectively is a feature of great advantage in that wear of both the blades on the roll 176 and the rubber on the bed roll 106 may be compensated for. The eccentric mounting permits adjustment to place the axes referred to in the same plane regardless of wear and feed roll spring pressure is thereby not permitted to influence the pressure of the bed roll against the bladed cylinder.

From this construction it will be seen that all operative parts are easily accessible and that the combination of the novel feed roll 204 and the quick-change feature or dead-center mechanism pertaining to the pinch roll 90 facilitate the treatment of either large or small skins in one machine. The novel feed roll 204 with its helical grooves 436 has an added advantage in that wear on the soft rubber surface of the bed roll 106 is evenly distributed. The fluid control system may be made as smoothly operative and as prompt in action as desired because of the easily changed or modified construction of the valve plunger 346.

Having thus described my invention, what I claim as new and desire to secure by Letters Patent of the United States is:

1. A machine for treating hides and skins comprising a frame, a rotatably bladed work treating roll mounted in fixed bearings on said frame, a feed roll resiliently mounted in spaced and parallel relation to said treating roll, a shaft mounted in the frame above and parallel to said treating roll, two swingable arms depending from said shaft, a bed roll and a pinch roll mounted on the said two arms to swing therewith as a unit toward and from said work treating roll, said feed roll being arranged to coact with and be

inserted between the pinch roll and the bed roll when the said unit is swung into "closed" position resulting in a "long grip" on a work piece draped over the pinch roll.

2. A machine for treating hides and skins comprising a frame, a stationary work treating roll rotatably mounted on said frame, a feed roll resiliently mounted in spaced and parallel relation to said treating roll, two curved arms depending from the upper part of said frame and pivoted thereon, a bed roll and a pinch roll mounted on the said two arms for movement therewith toward and away from said work treating roll and feed roll, said pinch roll being resiliently mounted on said two arms and said feed roll being arranged directly to coact with both the bed roll and the pinch roll when the two arms are swung toward the work treating roll.

3. A machine for treating hides and skins comprising a frame, a work treating roll journaled on said frame, a feed roll journaled in arms pivoted on said frame, said arms having fingers extending away from said work treating roll, two depending arms journaled in the upper portion of said frame, a bed roll and a pinch roll supported by said two depending arms to cooperate with said feed roll for a "long grip" effect on a work piece draped over the pinch roll and said pinch roll being resiliently mounted with respect to said depending arms and arranged to be guided into and out from operative relation with the feed roll by said fingers.

4. A machine for treating hides and skins comprising a frame, a work treating roll journaled on said frame, a bed roll, feed roll and pinch roll mounted in cooperative relation with said work treating roll, means for yieldingly urging the said pinch roll toward said feed roll, a dead-center mechanism for moving and holding the said pinch roll away from its operative position relative to the other rolls, and means for moving the said bed roll and pinch roll as a unit in a direction normal to the axis of the said work treating roll.

5. A machine for treating hides and skins comprising a frame, a work treating roll journaled on said frame, a soft rubber-covered bed roll mounted in cooperative relation with said work treating roll, a grooved feed roll mounted in cooperative relation with the said bed roll, a pinch roll yieldingly mounted with respect to said frame and arranged to cooperate with the said feed roll, and a lever operated dead-center mechanism for lifting and holding the said pinch roll away from the said feed roll.

6. A machine for treating hides and skins comprising a frame, a helical bladed work treating roll journaled on said frame, a feed roll resiliently mounted in spaced and parallel relation to said treating roll, two depending arms pivoted to an upper portion of said frame, a bed roll mounted on the said two arms to swing therewith as a unit into cooperative relation with the work treating roll and the feed roll, the helical blades of said work treating roll being such as to spread a given work piece on said bed roll, said bed roll having a resilient surface material such as soft rubber, said feed roll having longitudinally uniformly spaced grooves and also helical grooves to the opposite hand, and said helical grooves being formed with sharp shoulders in the feed roll directed away from the ends thereof for counteracting any undue effect of the helical blades of the work treating roll bodily to move the work laterally.

7. A machine for treating hides and skins com-

prising a frame, a work treating roll having helical blades journaled on said frame, a bed roll mounted in cooperative relation with said work treating roll and having a yielding surface material for supporting a work piece thereon, a feed roll mounted in cooperative relation with said bed roll and said feed roll having longitudinal grooves and also helical grooves, and means for driving the work treating roll and the feed roll in such directions that the helical blades tend to spread the work and the feed roll tends to hold the work along a path normal to the axes of the rolls.

8. A machine for treating hides and skins including a work treating roll, a bed roll cooperating with said work treating roll and having a soft covering material thereon, and a feed roll arranged in cooperative relation with said bed roll, said feed roll having longitudinal as well as helical grooves, the helical grooves forming sharp shoulders in the feed roll directed toward a path of feed normal to the axes of the rolls.

9. A machine for treating hides and skins comprising, a frame, parallel and spaced work treating and feeding rolls mounted on said frame, said feeding rolls including a pinch roll held in operative position by spring means, a dead-center mechanism mounted on said frame and attached to said pinch roll, and a handle for operating said mechanism to lift and hold the said pinch roll against said spring means and away from cooperative relation with the other rolls.

10. A machine for treating hides and skins comprising a frame, a work treating roll journaled in a fixed position on said frame, a feed roll resiliently mounted on said frame in parallel and spaced relation to said treating roll, a bed roll and a pinch roll mounted in pivotal relation to said frame to move into and away from cooperative relation with said work treating roll and said feed roll, a fluid pressure motor for moving the bed roll and pinch roll into and away from said relation, a valve for controlling the flow of fluid to said fluid pressure motor, and an exhaust valve for controlling the exhaust of fluid from said motor, said exhaust valve comprising a cylinder mounted on said frame with a plunger therein, said plunger being linked with the bed and pinch rolls simultaneously to move therewith and having annular grooves to regulate the passage of exhaust fluid between the plunger and the interior wall of the said cylinder.

11. A machine for treating hides and skins comprising a frame, a work treating bladed roll journaled on said frame, a bed roll bodily movable on said frame into and away from operating relation with respect to said bladed roll, a fluid pressure system for controlling the bodily motion of said bed roll, an exhaust valve for the pressure fluid of said system comprising a cylinder and a plunger in said cylinder, and said plunger being linked to said bed roll for a corresponding motion and having annular grooves for regulating the exhaust of the fluid between the walls of the cylinder and the plunger.

12. A machine for treating hides and skins comprising a frame, a bladed work treating roll journaled in fixed bearings on said frame, a feed roll resiliently mounted in spaced and parallel relation to said treating roll and having longitudinal as well as helical grooves, a shaft above and parallel to said treating roll and mounted in the upper portion of the machine frame, two arms depending from said shaft and swingable with respect to said frame, a bed roll and a pinch roll mounted on the said two arms to swing therewith.

as a unit between "open" and "closed" positions for the bladed and bed rolls, said feed roll being arranged to separate the pinch roll from the bed roll when the rolls are in the closed positions, a dead-center mechanism for raising or lowering the said pinch roll away from or into cooperative relation with the other rolls, and a fluid pressure operated system for opening or closing the rolls including an exhaust valve having a cylinder and a plunger therein, the said plunger being connected for movement with said two arms and having annular grooves for regulating the passage of fluid between the walls of the cylinder and the plunger.

13. A machine for treating hides and skins comprising a frame, a bladed work treating roll journaled in fixed bearings on said frame, a feed roll journaled in curved arms having pivot connections to said frame, two arms depending from and pivoted upon an axis at the upper portion of said frame and carrying a bed roll in parallel relation with said bladed roll, and the said feed roll pivot connections being adjustable to bring the center line of the feed roll into the same

plane as that of the said axis and the center line of the bed roll.

14. A machine for treating hides and skins comprising a frame, a stationary work treating roll rotatably mounted on said frame, a feed roll pivotally mounted by eccentric adjustment means in spaced and parallel relation to said treating roll, two arms depending from and pivoted upon the upper part of said frame, a bed roll journaled on said two arms and in parallel relation to said treating roll, said two arms being swingable to bring the bed roll and treating roll into cooperative relation, and the center line of the feed roll being between the center line of the bed roll and the axis of rotation of the curved arms and in the same plane as that of said center line and axis during said cooperative relation.
